UNITED STATES PATENT OFFICE.

JOSEPH O. DECKERT, OF PHILADELPHIA, PENNSYLVANIA, ASSIGNOR OF TWO-THIRDS TO CHARLES H. MANN AND HARRY A. PRIZER, OF PHILADELPHIA, PENNSYLVANIA.

BOOK-LEAF.

No. 801,652.

Specification of Letters Patent.

Patented Oct. 10, 1905.

Application filed January 6, 1905. Serial No. 239,867.

To all whom it may concern:

Be it known that I, JOSEPH O. DECKERT, a citizen of the United States, residing in the city and county of Philadelphia, State of Pennsylvania, have invented a new and useful Improvement in Book-Leaves, of which the following is a specification.

My invention relates to books, ledgers, or other assemblages of leaves, tightly or loosely bound, in which it is desirable to have leaves lie flat when the book is bound.

My invention relates more specifically to leaves themselves; and it consists in a construction whereby the leaves are rendered more flexible at the desired portion of each leaf than throughout the remainder of the leaves.

My invention consists in weakening a portion of the sheet against bending strain and reducing the resistance to bending of a portion of this weakened part.

My invention relates more particularly to a construction wherein the surface fibers of a portion of paper which would otherwise be held in restraint by the sizing used in connection with the surface-forming process are either not sized during manufacture or are slightly separated or relieved from their restraint thereafter without removing the same or reducing the thickness of the paper, whereupon the leaf will lie flat when in position in an open book or binder.

In order that that portion of the leaf from which the size has been omitted or where the fibers have been relieved from restraint may not be less dense, and hence of appreciable greater thickness than the rest, it may be rolled without the use of a sizing solution.

Figure 1 is a perspective view of a leaf intended for a book or binder. Fig. 2 is an enlarged fragmentary perspective of the same. Fig. 3 is a perspective, with the supports removed, of a surface-forming device by which the paper may be prepared.

Similar numerals of reference indicate corresponding parts in the figures.

Referring to the drawings, the sized leaf 10 is provided with a portion 11, from which the size-finish has been omitted or whose fibers 12 have been relieved from the cohesion due to the surfacing process in any manner. The portion 11, from which the sizing is omitted or has been removed, is preferably

uniformly so treated throughout the extent of the same, but may be varied, if desired. The treatment may be extended to both sides 55 of the leaf, as shown in Fig. 2, or may be upon one side of said leaf only.

When both sides of the leaf are without sizing, the portions lacking sizing may be opposite to each other on the leaf, as in Fig. 2, or 60 arranged in any other suitable manner. I may omit the sizing in the process of manufacture of the paper, as above stated, or the fibers may be freed from the restraint due to the surfacing process, while the said fibers are retained 65 in their entirety and the thickness and strength of the paper at the point treated are not impaired. The surface fibers may be freed from the restraint due to sizing in any suitable manner, as by subjecting the portion 70 of the surface of the paper to light brushing or beating, as by a rotating brush, which lifts up the fibers of the paper from the position to which they have been forced by the rolling of the surfacing process and in which they 75 have been held by the action of the sizing or surface-forming solution.

In Fig. 3 is shown an apparatus for finishing a paper with a size throughout a portion of its surface and compressed without sizing 80 throughout that portion intended to be left more flexible than the remainder.

13 and 14 and 13' and 14' illustrate two pairs of rollers arranged in pairs longitudinally and vertically and provided with a tank 16 in 85 which the rollers 14 and 14' lie and from which these rollers receive the sizing solution and with any suitable apparatus 16' for supplying size to the rollers 13 and 13'. At a suitable distance from these rollers and upon 90 shafts parallel to their shafts are arranged rollers 17 and 17', not provided with sizing solutions, and of such width and so located that a sheet of paper 19 passed through the sets of rollers in the direction of the arrow 95 will receive a sized surface upon its outer border produced by rollers 13, 14, 13', and 14' and the sizing solution, while the portion of the surface lying between rollers 13 and 13' will not receive sizing material, but will be 100 acted upon only by rollers 17 and 17'. Sheet 19 will by this method of manufacture be sized throughout a desired portion of its width.

At a suitable point in the portion of the

leaf which is freed from the strain due to the sizing process or from which the sizing has been omitted I crease the paper, as at 20, preferably creasing it at top points 21 and 22 in 5 opposite directions. These creases are but slightly evident in the finished page, but when so made in a leaf of which the surface fibers are loosened the center fibers are sufficiently disturbed to permit thereafter free bending of 10 the leaf in either direction. The creases are preferably located in that part of the leaf which is free from the restraint due to the sizing operation and in the portion of it farthest removed from the binding edge.

15 It will be evident that various changes may be made by those skilled in the art which will come within the scope of my invention, and I do not, therefore, desire to be limited in every

instance to the exact construction herein shown and described.

Having thus described my invention, what I claim as new, and desire to secure by Letters Patent, is—

1. A sheet or leaf of paper or similar material, a portion of which offers less resistance 25 to bending strains than the remainder, in combination with a crease within said portion.

2. A sheet or leaf of paper or similar material uniformly offering less resistance against bending strain throughout a section of its area 30 than in the remainder of the sheet and weakened throughout a portion of the said section.

JOSEPH O. DECKERT.
